UNITED STATES PATENT OFFICE.

STEPHEN WARE AND CHARLES WARE, OF HORNSBY, NEAR SYDNEY, NEW SOUTH WALES, AUSTRALIA.

RAIL AND FISH JOINT.

1,004,945.

Specification of Letters Patent.

Patented Oct. 3, 1911.

Application filed February 21, 1910. Serial No. 545,172.

To all whom it may concern:

Be it known that we, STEPHEN WARE and CHARLES WARE, both subjects of the King of Great Britain, and residing at Hornsby, 5 near Sydney, in the State of New South Wales and Commonwealth of Australia, have invented a new and useful Improved Rail and Fish Joint, of which the following is a specification.

10 This invention has been devised in order to insure that traveling rolling stock will bear on the ends of conjoined lengths of rails at each joint which joint has a solid, or single sleeper support thereunder (instead of twin sleepers) and that the rail ends of each joint will remain in the same horizontal plane as the rolling stock is passing over said joint thereby minimizing the 15 concussion of the wheels upon the ends of the lengths of rails and this without hindrance of provision for ordinary expansion and contraction of the rail lengths.

According to this invention a rail and fish joint comprises the peculiarly shaped 20 or formed ends of the rail lengths a wider sleeper and ordinary fish plates and bolts though preferably a novel construction of fish plate is used on one side of the joint. The respective ends of the rail lengths are 25 formed one with a projection or tenon in the head or tread and the other with a complementary mortise or slot so that when the oppositely formed ends are butted together a horizontal long splice is formed 30 which presents a continuous tread surface.

The novel construction of fish plate consists of a plate (with ordinary oval bolt holes) having depending lugs to take 35 against the sides of a sleeper and so keep the sleeper always under the rail joint. In laying the rails the joints of one rail are kept intermediate of the joints of the other rail of that track. In laying the rails for double lines the ends may be laid for each 40 side of the track so as to have the points of the tenons of the rail ends all leading points though there is no danger of fouling of the joints of single lines.

In order that a practical application of 45 this invention may be understood reference will now be made to the drawings accompanying and forming part of this complete specification in which—

Figure 1 is a perspective view of an improved rail joint for railways constructed

according to this invention Figs. 2 and 3 being respectively views of the joint taken apart showing the butting ends of the rails at an angle to their normal positions. Fig. 4 is a partial longitudinal-sectional view 60 and Fig. 5 is a transverse sectional view of the joint.

One end of a rail 6 is formed with a projection or tenon 7 extending from the tread 8 and the other end has a complementary 65 mortise or slot 9 in the tread 8 and has an orifice or passage 10 from the base or heel of said mortise 9 through the tread for the escape of grit or moisture that may find its way into the mortise. 70

A fish plate 11 constructed according to this invention has in addition to the ordinary bolt holes depending lugs 12 at each end angled so as to fit over the base 13 of the rail and project downwardly against 75 the sides of the sleeper 14.

For double tracks wherein the rolling stock passes only one way one depending lug on the fish plate might suffice in which case it would take against the trailing side 80 of the sleeper. The sleeper should be of sufficient width to reach under the ends of the rails to just beyond the last bolt hole of that fish joint and will then take between the depending lugs of the specially 85 constructed fish plate but in the event of sleepers narrower than the length of fish plates being used the ends of the depending lugs will be angled in toward the sleeper. These projecting lugs 12 are 90 formed in a manner especially adapting them to be thus forced in to firmly engage and grip the sleeper 14. Each such lug 12 comprises, as clearly shown at Fig. 1, a depending sleeper-engaging prong or downwardly projecting lower part, and an upper horizontal part or shank, which is shown as overlying the base flange of the rail 6 and which joins or unites the lower edge of the fish plate 11 with the upper end 95 of the sleeper engaging prong. The horizontal shank of the lug 12 is adapted to be bent to permit the prong to closely engage the tie or sleeper 14, and such bending may be readily effected simply by properly striking the lug with a track sledge such as is commonly used for driving the usual spikes. 100

In use the lengths of rails are butted together with the joint on a sleeper 14 the tenon or projecting tongue 7 of one rail 110

taking in the mortise or recess 9 of the other rail and both rails held together by ordinary fish plates and bolts and preferably one such fish plate having depending lugs 5 12 to keep the sleeper always under the joint should the rails creep.

Having now particularly described and ascertained the nature of our said invention and in what manner the same is to be 10 performed we declare that what we claim is:—

A rail joint for railways comprising, in combination, two rails provided with treads and having abutting engaging ends, 15 one of the rails having a recess in its tread and the other rail being provided with a

projecting tongue fitting in the recess, the recessed tread having a drainage and outlet aperture for the recess extending through the tread from the inner part of the recess 20 downwardly and laterally outwardly and opening below the tread, and means for retaining the abutting ends of the rails in engaged relation.

In testimony whereof we have signed our 25 names to this specification in the presence of two subscribing witnesses.

STEPHEN WARE.
CHARLES WARE.
